COMBINATION STORAGE AND CARRYING CASE

Marcel A. Monier, Baltimore, and Gerald G. Seidl, Timonium, Md., assignors to The Black and Decker Manufacturing Company, Towson, Md., a corporation of Maryland

Filed May 23, 1960, Ser. No. 60,694

Term of patent 14 years

(Cl. D58—12)

FIG. 1

FIG. 2

FIG. 5

We claim:

The ornamental design for a combination storage and carrying case, as shown.
